UNITED STATES PATENT OFFICE

JAMES E. McDANIEL, OF COLUMBIA, SOUTH CAROLINA

LOCOMOTIVE THROTTLE AND DRIFTING VALVE MECHANISM

Application filed January 19, 1929. Serial No. 333,678.

This invention relates to improvements in locomotive throttle and drifting valve mechanism, one object of the invention being the provision of a single manually operated valve which combines in its structure both a throttle and drifting valve and which is operative either to regulate the admission of steam to the cylinders for operating the locomotive under tractive action, or to admit a certain amount of the steam to the cylinders through the usual steam line when the locomotive is drifting in order to prevent the formation of vacuum in the cylinders, to prevent the entrance of grit into the cylinders, to afford the proper lubrication to the cylinders, and to prevent the carbonization of oil within the cylinders.

Another object of this invention is the provision of a combined throttle and drifting valve which, when any steam leaks past the valve, while the valve is in a normally closed position and the locomotive is at rest, will direct said leakage away from the cylinders, preferably to a water feed tank where such steam may be utilized for heating purposes, and thus prevent passage of the leaking steam to the cylinders where it might cause an accidental movement of the pistons.

Still another object of this invention is the provision of a combined throttle and drifting valve of the piston type wherein the piston is subject on its opposite sides to equal pressure of steam from the boiler so that the valve will always be balanced in whatever position it may be set and thus have no tendency to be moved by steam pressure from such position.

With the foregoing and other objects in view, which will appear as the description proceeds, the invention resides in the combination and arrangements of parts and in the details of construction hereinafter described and claimed, it being understood that changes in the precise embodiment of the invention herein disclosed can be made within the scope of what is claimed without departing from the spirit of the invention.

In the drawings:—

Figure 1 is a diagrammatic view of a locomotive having the present invention applied

thereto. It is to be understood, however, that the invention is applicable to any type of locomotive.

Figure 2 is a vertical central sectional view, on a larger scale, through the steam dome of a locomotive embodying the present invention and showing the valve in normally closed position.

Figure 3 is a section taken on line 3—3 of Figure 2.

Figure 4 is a vertical central sectional view through the valve seat and valve illustrated in Figure 2, the valve being shown in the position it assumes during the drifting of the locomotive.

Figure 5 is a view similar to Figure 4 showing the valve in the position it assumes when in full open position.

Figure 6 is an enlarged view of a fragment of the wall of the valve cylinder showing a modified shape of the ports for the passage of steam to and from the valve cylinder.

Figure 7 is a sectional view through the upper and lower steam controlling pistons showing a modified arrangement of packing rings and ports in said pistons.

Referring to the drawings, B designates the boiler of the locomotive, C one of the cylinders, E the exhaust from said cylinder, and S the stack, all of the same being of usual construction and being shown only diagrammatically.

The steam dome 8, as here shown, is provided with a removable head 8' formed as an annulus and secured rigidly in place in the dome, a cover 9 being removably attached to the head. Said cover is provided with a central opening 10' for the reception of a removable cap 10 provided with a stuffing box 11, the purpose of which will presently appear. Depending in the dome from the cover 9 is a casing 12 forming a steam chamber.

The casing 12 has at its upper end a plurality of inlet ports 13 for the admission of steam thereto from the steam dome.

A valve cylinder 14, of smaller external diameter than the internal diameter of the casing 12 and preferably formed integrally with the bottom of the casing 12, extends up-

60

70

75

80

85

90

95

100

wardly from said bottom to a point below the inlet ports 13 of said casing. This cylinder has its upper end open for the admission of steam thereto from the casing 12.

5 A substantially cylindrical jacket 15, concentric with the cylinder 14, surrounds the cylinder 14 with its peripheral wall spaced from the walls of the casing 12 and cylinder 14 and its upper and lower walls connected at 10 one side of the jacket to the wall of the casing 12, thus forming in the casing 12 an upper compartment 16 and a lower compartment 17 connected by the space 18 between the peripheral wall of the jacket 15 and the 15 wall of the casing 12. A conduit 19 is connected at one end to the jacket 15 and at its other end to the steam chests of the driving cylinders of the locomotive.

A row of horizontally aligned and preferably substantially diamond shaped ports 20 20 are formed in the wall of the cylinder 14 above the upper wall of the jacket 15 for the admission of steam from the upper compartment 16 of the casing 12 to the upper portion 25 of the cylinder 14. A pair of vertically spaced horizontal rows of similarly shaped ports 21 and 22 are formed in the wall of the cylinder 14 between the upper and lower walls of the jacket 15 for the passage of steam from 30 the cylinder 14 to the space 18 between the cylinder 12 and the jacket 15 and thence to the conduit 19; and a horizontal row of similarly shaped ports 23 are formed in the 35 wall of the cylinder 14 between the lower wall of the jacket 15 and the bottom of the casing 12 to admit steam from the lower compartment 17 of the casing 12 to the lower end of the cylinder 14.

The casing 12 has an opening in its bottom 40 concentric with the cylinder 14, and a cylinder 24 of smaller diameter than and concentric with the cylinder 14 depends from the bottom of the casing 12 below said opening into the locomotive boiler. The cylinder 45 24 has an opening 25 in its wall approximately midway between its ends to which a pipe 35 is connected and extends through the wall of the steam dome 8 for a purpose to be explained hereinafter. A cap 26 is mounted 50 on the lower end of the cylinder 25 and is provided with openings 27 for the admission of steam from the boiler to the lower end of the cylinder 25.

Valve means are provided for controlling 55 the flow of steam from the upper and lower compartments 16 and 17 of the casing 12 through the ports 20 and 23 into the upper and lower ends of the cylinder 14, and thence through the ports 21 and 22 to the jacket 15 60 and also for conveying to the port 25 of the cylinder 24 any steam which may leak past said controlling means when in closed position. Such means is shown as a valve, denoted generally as V, movable lengthwise of the 65 valve cylinder 14 and including a piston rod

28, a pair of upper spaced pistons 29 and 29' carried by said rod and working in the valve cylinder 14, together with a pair of lower spaced pistons 30 and 30' working in the cylinder 24. The pistons 29, 29' and 30 each 70 has a peripheral groove 31 connected by a radial bore 32 to a bore 33 extending longitudinally of the piston rod 28 between the pistons 29 and 30. In Figures 2, 4 and 5 each of the pistons 29, 29' and 30 is shown as 75 carrying on its periphery a pair of rings 34, one above and the other below the peripheral groove 31 thereof, to prevent, so far as possible, leakage of steam past said pistons. In Figure 7, the rings 34' of the upper piston 29 80 are shown as being both located above the peripheral groove 31 of said piston and the rings 34' of the piston 29' as both located below the peripheral groove of said piston.

The peripheral grooves 31 of the pistons 85 29 and 29' are spaced apart a distance equivalent to the distance between the centers of the ports 20 and 22 of the cylinder 14, so that, when the peripheral groove 31 of the piston 29 is opposite the ports 20 the peripheral 90 groove of the piston 29' will be opposite the ports 22, or, when the peripheral groove 31 of the piston 29 is opposite to and is covered by that portion of the wall of the cylinder 14 above the ports 20, the peripheral groove of 95 the piston 29' will be opposite to and be covered by that portion of the wall of the cylinder between the ports 21 and 22.

The peripheral groove 31 of the piston 30 100 is spaced at such a distance from the peripheral groove 31 of the piston 29' that, when the valve is in closed position, as shown in Figure 2, that is to say, with the groove 31 of the piston 29 covered by the portion of the wall of the cylinder 14 between the ports 20 105 and the ports 21 and with the groove 31 of the piston 29' covered by the portion of the wall of the cylinder 14 between the ports 22 and 23, the peripheral groove of the piston 30 will be in alignment with the port 25 of 110 the cylinder 24.

When the valve is in its closed position shown in Figure 2 steam will be prevented by the pistons 29 and 29' from passing from the upper and lower ends of the cylinder 14 115 to the intermediate part of said cylinder, that is to say, to the part of the cylinder surrounded by the jacket 15; but if any steam should escape past the uppermost ring 34 of the piston 29 or past the lowermost ring 34 120 of the piston 29' it will pass into the peripheral groove 31 and radial bore 32 of such piston, through the longitudinal bore 33 of the piston rod, radial bore 32 and peripheral groove 31 of the piston 30, and thence 125 through the port 25 in the wall of the cylinder 24 and the pipe 35 either to the atmosphere or to the feed water tank 36 for the boiler for preheating the water in such tank.

If the valve be moved upwardly into the 130

position shown in Figure 4 to bring the peripheral grooves 31 of the pistons 29 and 29' into registry, respectively, with the ports 20 and 22 of the cylinder 14, steam will pass from the space 16 through the port 20, the peripheral groove 31 and radial groove 32 of the piston 29, the longitudinal bore 33 of the piston rod, the radial bore 32 and peripheral groove 31 of the piston 29', through the port 22 into the jacket 15 and thence through the conduit 19 to the driving cylinders of the locomotive, thus supplying a sufficient quantity of steam to the latter cylinders for drifting purposes.

15 If, on the other hand, the valve be moved to its uppermost or full open position shown in Figure 5, steam will pass from the space 18 through the ports 20 and 23 into the cylinder 14 and out of the ports 21 and 22 to the jacket 15 and thence through the conduit 19 to the driving cylinders of the locomotive.

20 The area of the upper side of the piston 29 subject to steam pressure from the boiler through the open upper end of the cylinder 14 and through the ports 20 in the wall of said cylinder plus the area of the upper side of the piston 30 subject to steam pressure from the boiler through the ports 23 in the wall of said cylinder is equivalent to the area 25 of the lower side of the piston 29' subject to steam pressure from the boiler through the ports 23 plus the area of the lower side of the piston 30' subject to steam pressure from the boiler through the openings 27 in the cap 30 at the lower end of the cylinder 24; and the area of the lower side of the piston 29 is 35 equivalent to the area of the upper side of the piston 29'. Therefore, the valve comprising the pistons 29, 29', 30 and 30' will always be balanced in whatever position the 40 valve is set.

45 Although the ports 20, 21, 22 and 23 in the wall of the cylinder 14 may be of any shape, it is advantageous to make them of diamond shape, as shown in Figures 2, 4 and 5, or pointed at one end, as at 20' in Figure 6, because when they are so shaped only a comparatively small amount of steam can pass through them during the early part of the movement of the pistons 29 and 29' past them when the valve is moved toward open position, and the amount of steam permitted to pass through said ports during the further movement of the pistons will increase at a rate greater than the rate of movement of the pistons. Thus sudden admission of steam to the driving cylinders and sudden starting of the locomotive is avoided.

50 Means operable from the cab of the locomotive are provided for moving the pistons 29, 29', 30 and 30' into closed position, or into drifting position, or into full open position. Such means are here shown as a rod 37 extending through the stuffing box 11 in the cap 10 and having its lower end connect-

ed to the upper side of the piston 29, as at 38, and its upper end connected to a lever 39 fulcrumed between its ends on an arm 40 extending upwardly from the cover 9. A link 41 connects the other end of the lever 39 to one arm of a bell-crank lever 42 fulcrumed on the steam dome, and a second link 43 extends from the other end of the bell-crank lever 42 into the cab of the locomotive where it is connected to the throttle lever 44. The throttle lever 44 moves across a segment 45 marked to indicate closed position, drifting position and open position of the valve when the throttle lever is opposite such marks.

55 From the foregoing description, it will be evident that a combined throttle and drifting valve has been devised which is readily applicable to any type of locomotive, and which will render it unnecessary to provide automatic drifting valves to prevent vacuum in the cylinders when the locomotive is drifting, and also that in case of any leakage past the pistons when the valve is closed and the locomotive is at rest, the steam is directed away from the throttle line so that none of it can enter the power cylinders to accidentally operate the pistons of the locomotive, but, as here shown, it is directed to a feed water heater where it can be utilized for that or other purposes.

60 By this construction, should the pistons leak, it is only necessary to bodily remove the complete valve through the top of the dome and renew the necessary rings, instead of having to resort to the grinding of the valves and seats as is necessary in the case of the valves commonly in use at present.

65 I claim:—

1. A combined throttle and drifting valve mechanism, including a main casing insertable within the steam dome of a boiler, a valve casing mounted in the main casing and provided with the inlet ports adjacent the ends thereof and with intermediate outlet ports, an outlet chamber surrounding the valve casing and into which said outlet ports lead, and a reciprocatory valve mounted in the valve casing and comprising two spaced pistons to control the flow of steam from the inlet ports to and through the outlet ports.

70 105 110 115 120 125 130

2. A combined throttle and drifting valve mechanism, including a main casing insertable within the steam dome of a boiler, a valve casing mounted in the main casing and provided with inlet ports adjacent the ends thereof and with intermediate outlet ports, an outlet chamber surrounding the valve casing and into which said outlet ports lead, a reciprocatory valve mounted in the valve casing and comprising two spaced pistons to control the flow of steam from the inlet ports to and through the outlet ports, the main casing having an extension concentrically of the valve casing provided with an outlet port open to the exterior, and a piston carried by

the valve and slidably in said extension to control said outlet port and the diverting of the steam to the exterior.

3. The combination with a locomotive steam dome, of a combined throttle and drifting valve mechanism mounted therein and including a cylindrical valve casing provided with spaced inlet and outlet ports, a valve mounted in said casing comprising a pair of connected spaced pistons for controlling the passage of steam from the inlet to the outlet ports, each of said pistons having a port in its periphery communicating with the port in the periphery of the other piston, said pistons being shiftable to align their ports, respectively with an inlet and outlet port of said valve casing.

4. The combination with a locomotive steam dome, of a combined throttle and drifting valve mechanism mounted therein and including a cylindrical valve casing provided with spaced inlet and outlet ports, a valve mounted in said casing and comprising a pair of spaced pistons for controlling the admission of steam from the inlet to the outlet ports, said valve casing having at one of its ends an extension provided with a lateral outlet port, a pipe leading from said lateral outlet port to the exterior of the steam dome, a third piston working in said extension, each of said pistons having a port in its periphery, and means connecting said pistons and having a conduit communicating with the ports in the peripheries of said pistons, the peripheral port of said third piston registering with the port of the valve casing extension when the first named pistons are positioned to prevent the passage of steam through the inlet and outlet ports of said casing.

40 5. The combination with a steam dome, of a combined throttle and drifting valve mechanism including a valve casing provided with intermediate outlet ports and inlet ports at opposite sides of said outlet ports, said casing being provided with an extension having an outlet port between the ends thereof, means connecting the latter port to the exterior of the steam dome, a valve comprising a pair of pistons working in said valve casing and movable into and out of position to establish communication between said inlet and outlet ports, and a third piston working in said extension, each of said pistons having a peripheral port, and means connecting said pistons in spaced relation and having means connecting the peripheral ports of said pistons, the peripheral port of said third piston being in registry with the outlet port of said extension when first named pistons are positioned to close communication between the inlet and outlet ports of said casing and thereby convey away steam leaking past said first named pistons.

60 6. The combination with a steam dome, of a combined throttle and drifting valve mech-

anism including a valve casing provided with intermediate outlet ports and inlet ports at opposite sides of said outlet ports, said casing being provided at one end with an extension having an outlet port between the ends thereof, means connecting the latter port with the exterior of the steam dome, a valve comprising a pair of spaced pistons operably connected together and working in said valve casing, to control the passage of steam from said inlet ports to said outlet port, a third piston operably connected to said pair of pistons and controlling the outlet port of the extension, said pistons being provided with communicating ports, the port of said third piston being out of alignment with the outlet port of the extension when the ports of said first-named pistons are in alignment, respectively, with an inlet port and an outlet port of the valve casing.

7. In a locomotive having a steam dome and driving cylinders, a combined throttle and drifting valve, comprising a cylinder having a main portion and an extension of smaller diameter than its main portion, said main portion having a pair of circumferential spaced rows of outlet ports between its ends and an inlet port between each of its ends and each of said outlet ports, means connecting said outlet ports with the driving cylinders of the locomotive, said inlet ports being spaced, respectively, the same distance from said outlet ports as said rows of outlet ports are spaced apart and said extension having an outlet port in its wall communicating with the exterior of the steam dome, a pair of peripherally grooved main pistons working in the main portion of said cylinder and a peripherally grooved secondary piston working in the extension of said cylinder, and means connecting the peripheral grooves of said main and secondary pistons, said pistons being unitarily shiftable to place one of the main pistons between one end of the main portion of the cylinder and one of the inlet ports and the other between said rows of outlet ports with the groove of the secondary piston out of alignment with the outlet port of the extension, or to place each of the main pistons between one of the inlet ports and one of the outlet ports and the groove of the secondary piston in alignment with the outlet port of the extension.

In testimony whereof I have hereunto set my hand.

JAMES E. McDANIEL.
